ARNOLD E. SWANSON AND DANIEL MORGAN, OF DES MOINES, IOWA.

CLOSET REENFORCING FLANGE.

Application filed March 5, 1925. Serial No. 13,187.

The object of our invention is to provide a simple, reenforcing closet flange wherein soil pipes may be easily and conveniently secured thereto.

5 Still a further object is to provide a reenforcing closet bowl flange having a horizontal, annular flange, having a vertical rim extending downwardly from the inner edge of the horizontal flange, and terminating in 10 an inclined flange bent inwardly to form a support for the soil pipe.

It may be here mentioned that usually the 15 soil pipe in connection with the bowl is of such diameter as to receive therein the bowl connecting flange.

It is our object to provide a reenforcing flange so that the soil pipe of substantially the same interior diameter may be used as the interior diameter of the bowl connecting 20 flange without weakening the connection on account of the bossing out of the lead soil pipe, it being protected by the reenforcing flange.

Still a further object is to provide a 25 slightly modified form of reenforcing flange wherein the reenforcing flange may be directly connected to a soil pipe of the cast iron type, by what is known as the calking method.

30 With these and other objects in view, our invention consists in the construction, arrangement and combination of the various parts of our device, whereby the objects contemplated are attained, as hereinafter more 35 fully set forth, pointed out in our claim, and illustrated in the accompanying drawings in which:

Figure 1 is a perspective view of our improved reenforcing closet flange.

40 Figure 2 is a sectional view through the same, showing a complete installation of the soil pipe and closet bowl; and

Figure 3 is a slightly modified form 45 wherein the reenforcing flange is connected direct to a cast iron pipe by what is known as the calking method.

In the accompanying drawings, we have 50 used the reference character A to indicate generally our reenforcing flange, which comprises three main sections.

The three sections of the reenforcing flange A are the horizontal flange 10, the vertical rim 11 and the inclined inwardly extending flange 12.

55 The rim 11 is formed on the inner edge of

the flange 10, which is in the shape of a flat ring.

The flange 10 is adapted to rest directly upon floor boards 13, which are positioned upon a sub-floor 14, as clearly shown in 60 Figure 2 of the drawings.

An opening 15 is cut in the floor boards 13, and the sub-floor 14 for receiving the vertical rim portion 11 of the reenforcing flange A.

65 The inclined flange 12 extends inwardly from the lower edge of the rim 11.

A soil pipe 16 of lead construction is shown resting against the rim 11 and the inclined flange 12.

70 The lead soil pipe 16 is flared out, and is adapted to rest against the rim 11 and to be supported upon the inclined flange 12.

It is an easy matter to flare or stretch out 75 the lead of the soil pipe 16 at the connection with the reenforcing flange A.

The flaring out of the lead soil pipe to fit 80 the reducing flange A is what is commonly known as a "boss job", the lead being flared out after the pipe 16 is in place.

The horizontal flange 10 is formed with a 85 number of bayonet slots 17 for receiving bolts 18. The bayonet slots 17 are of the ordinary construction used in connection with plumbing work.

A closet bowl 19 of the ordinary type rests over the horizontal flange 10 and completely conceals it. This is done by the use 90 of an overhanging flange 20 through which the bolts 18 extend.

At the upper edge of the soil pipe 16 we use sole solder 21 for filling the connection between the soil pipe 16 and the reenforcing flange A.

A gasket 22 rests upon the horizontal 95 flange 10 and seals the connection between the closet bowl 19, and the reenforcing flange A.

The closet bowl 19 is formed with a neck or discharge top 23, which extends into the 100 lead soil pipe at the place where it is flared out, as clearly shown in Figure 2 of the drawings.

By providing the reenforcing flange, we 105 are able to make a connection between the lead soil pipe 16, and the closet bowl using the same diameter of pipe for the soil pipe, as is the inside diameter of the neck 23.

In Figure 3 of the drawings, we have 110 shown an extension 24 on the lower edge of

the inclined flange 12, which is directly connected to a cast iron soil pipe 25 at the bell end 26.

The extension 24 is tubular shaped and is formed with side walls, which are somewhat inclined outwardly and has its lower end beaded, as at 27.

The end 27 rests in the bell end 26 of the soil pipe 25.

10 The space between the bell end 26 and the extension 24 is filled with lead or other corking material 28 for forming a positive seal between the closet reenforcing flange and the soil pipe 25.

15 By providing the reenforcing flange A, we are able to use a soil pipe of less diameter than ordinarily used, and yet have a pipe of the same diameter that the discharge opening is in the closet bowl.

20 The reenforcing flange A is formed as a unit, and no other fittings are necessary in order to connect it to a particular diameter soil pipe.

25 Some change may be made in the construction and arrangement of the various parts of our invention, without departing from the real spirit and purpose of our invention, and

it is our intention to cover by our claim any modified forms of structure or use of mechanical equivalents, which may be reasonably included within their scope.

We claim as our invention:

The combination with a closet bowl having a flange and a neck and a lead pipe connected thereto by being expanded to fit over said neck, the inside of said pipe being substantially the same diameter as the inside of said neck, of a closet bowl fitting, comprising a flange portion adapted to rest on a floor, a tubular extension thereon, an inwardly projecting peripheral flange formed on the lower end of said tubular extension, whereby an opening is formed, substantially the same size as the outside diameter of said lead pipe, said tubular extension and said flange serving to support said lead pipe and the neck of said closet bowl, a gasket between the flange of said closet bowl and the flange portion of said closet bowl fitting and means for securing said flanges together.

ARNOLD E. SWANSON.
